(57) **CLAIM**

The ornamental design for a banner assembly, as shown and described.

DESCRIPTION

FIG. 1 is a bottom view of the banner assembly;
FIG. 2 is a front view of the banner assembly;
FIG. 3 is a left rear above view of the banner assembly;
FIG. 4 is a left rear below view of the banner assembly;
FIG. 5 is a left view of the banner assembly;
FIG. 6 is a rear view of the banner assembly;
FIG. 7 is a top view of the banner assembly;
FIG. 8 is a bottom view of the banner assembly in an alternate extended configuration of use;
FIG. 9 is a front view of the banner assembly in an alternate extended configuration of use;
FIG. 10 is a left rear of the banner assembly in an alternate extended configuration of use;
FIG. 11 is a rear view of the banner assembly in an alternate extended configuration of use; and,
FIG. 12 is a top view of the banner assembly in an alternate extended configuration of use.
The broken lines in the drawings depict portions of the banner assembly that form no part of the claimed design.

1 Claim, 12 Drawing Sheets
